[57] CLAIM

The ornamental design for a trousers, as shown and described.

DESCRIPTION

FIG. 1 is a front elevational view of trousers showing my new design;

FIG. 2 is a rear view thereof; and,

FIG. 3 is a perspective view thereof, the opposite side being a substantial mirror image, and the broken lines partially showing a human form being for illustrative purposes only and forming no part of the claimed design.

The broken lines shown on the trousers throughout the views are understood to represent conventional stitching.
